Atty.

UNITED STATES PATENT OFFICE.

HORACE H. KOUKA, OF CHICAGO, ILLINOIS, ASSIGNOR TO CHAMPION PNEUMATIC MACHINERY COMPANY, OF CHICAGO, ILLINOIS, A CORPORATION OF ILLINOIS.

AIR-COMPRESSING SYSTEM.

Application filed August 14, 1920. Serial No. 403,466.

To all whom it may concern:

Be it known that I, HORACE H. KOUKA, a citizen of the United States, and resident of Chicago, in the county of Cook and State of

5 Illinois, have invented certain new and useful Improvements in Air-Compressing Systems, of which the following is a specification.

My invention relates to improvements in 10 and has special reference to automatically controlled air compressors.

In the compression of free atmospheric air considerable moisture is condensed and furthermore more or less oil enters into the 15 compressed air from the cylinders of the compressor. This oil and moisture which is ordinarily stored with the compressed air is especially detrimental to automobile tires in which such compressed air is used.

20 It is usually difficult to start an electric driven air compressor, particularly one driven directly by an alternating current motor, when the compressor begins at once to discharge the air into the compressed air reser-

25 voir and considerable ability and ingenuity has been brought to bear upon this problem particularly in relation to automatic compressing plants for use in garages and the like.

30 By means of my present invention, I am enabled not only to readily start up the motor and compressor from an idle condition whether a direct current or an alternating current motor is used, but I am also 35 enabled to eliminate substantially all water and oil from the system, trapping it out of the compressed air before the air is delivered to the storage tank and automatically discharging all accumulations from the system 40 each time that the compressor is stopped.

45 My invention resides in a compressor and a source of power for operating same in combination with a power control, a trap interposed between the compressor and the storage tank and means operated by the power control for venting the trap each time the compressor is stopped, the vent being arranged to cause the discharge of all accumulated liquid from the trap each time the 50 vent opens.

55 My invention will be more readily understood by reference to the accompanying drawings forming part of this specification, and in which:—

Figure 1 is a fragmentary perspective

view of an electric driven compressor embodying my invention;

Figure 2 is a longitudinal vertical section of the motor control device;

Figure 3 is a transverse sectional view of 60 the control device on the line 3—3 of Figure 2; and

Figure 4 is a fragmentary longitudinal central vertical section of the compressor base particularly illustrating the baffles 65 therein.

In said drawings, 1 is an air compressor, 2 is an electric motor belted direct to the compressor by the belt 3 and 4 is the automatic control switch for stopping and starting the compressor in accordance with the increase and decrease of the air pressure in the storage tank. The compressor motor and control are all mounted on a single base plate 5 which in turn is on lugs 6 between 70 which and beneath the plate 5 is arranged and supported an air pressure tank or reservoir 7.

The air compressor shown is a two stage 80 compressor, the air being partly compressed in one cylinder 8 and then passed through a connecting pipe 9 provided with heat radiating veins 10 to the second cylinder 11. From the cylinder 11 the completely compressed air is delivered to the base 12 of the compressor which is provided with a pressure tight chamber 13. From the chamber 13 the compressed air escapes through a pipe 14 to the reservoir 7, the pipe 14 being controlled by a check valve 15 which prevents 85 the return of the air from the storage tank 7 to the chamber 13. The chamber 13 serves to trap out any liquid which may be carried in by the compressed air entering same, and I provide an inclined bottom 16 in this 90 chamber preferably extending downwardly from both ends toward the middle at which is formed a low point 17 where the liquid caught in the chamber 13 settles or accumulates. I connect this low point of the chamber by means of a vent pipe 18 to a vent 95 valve 19 arranged on the side of the motor control 4.

To insure the trapping of the liquid out of the air in the chamber 13 I provide a depending baffle wall 20 arranged at the end of the chamber into which the air is delivered through the pipe 21 from the compressor to the hollow base. Furthermore, as the compressed air leaves the

pump at a relatively high temperature, in other words "hot", I make the chamber 13 relatively large and its metallic walls in conjunction with the metal of the plate 5 6 serve as sufficient radiation to cool the air before it escapes to the tank 7 to insure the condensation of the water carried by the air.

This baffle wall cuts off a portion 22 of 10 the hollow base at the upper part of the end of the chamber 13 into which the compressed air is delivered. The baffle depends from the upper wall of the chamber to the inclined bottom wall thereof, the 15 lower edge 23 of the baffle being separated from the inclined bottom wall to provide a narrow transverse opening 24 through which the air can escape from the inlet chamber 22 to the main chamber 13. The 20 baffle thus forces all of the air down into contact with the inclined bottom wall of the chamber 13 and any liquid carried by the air is impinged against the inclined bottom and flows down to the low point 25 17 of the chamber 13. The delivery pipe 14 is connected with the highest point of the chamber 13 substantially midway between its ends so as to deliver substantially dry air to the tank 7.

The specific construction and operation 30 of the motor control 4 does not enter into this invention except to the extent that it controls the vent valve 19. It is sufficient to say that the specific control shown is 35 merely typical of a suitable control. It is provided with a control lever 25 pivotally mounted between its ends at 26. One end of the lever is connected to and is adapted to open and close a current control or 40 switch 27 and the other end is pivoted with a V-shaped projection 28 against which a roller 29 in the upper end of a spring pressed lever 30 is held. The roller is adapted to be raised and lowered by the pressure in the tank 7 through 45 the medium of a pressure operated diaphragm 31 which constitutes one wall of a pressure chamber 32 which is connected to the tank 7 by a pipe 33. Pressure on the 50 diaphragm 31 is adapted to be exerted upon a lever pivoted about the fixed pivot 29, which movement is transferred to a lever which pivots about the fixed pivot point 29. This latter lever has pivoted there- 55 on the lever 30. As the pressure in the tank 7 increases the roller travels up the lower incline 34 of the V-shaped end 28 until it passes the edge thereof at which time the spring pressure 60 to which the lever 30 is subjected causes the roller to advance on the upper incline 35 of the V-shaped end 28 thus depressing the end 28 of the lever 25. By this means the circuit supplying current to the motor 2 is broken and the compressor stops.

As the pressure decreases in the tank 7 the roller descends the upper incline 35 until it passes the end of the V-shaped end and then it acts to lift the end 28 of the lever 25 and again close the circuit to start the 70 motor. A spring 37 is provided which is adjustable to control the variation in pressure in the tank 7.

The switch 27 is a snap switch in that it 75 is suddenly opened and closed as the roller passes the apex of the V-shaped end 28, and I make use of this lever to control the vent of the chamber 13 in the base of the pump.

It is well understood that it is practically impossible to start an alternating current motor under load and as it is necessary to supply many of the compressors with such motors, I combine the idea of forcing the trapped liquid out of the chamber 13 with that of arranging the compressor so that as it starts it does not have to immediately deliver its compressed air against the storage pressure. In other words, I interpose a receiving chamber 13 80 between the compressor and the storage tank 7, which is of sufficient capacity in relation to the size of the pump, so that the motor shall have attained a working speed before the pressure rises high 85 enough therein to hold the motor back. I exhaust the air from this intermediate chamber when the compressor stops and it is automatically closed as the compressor 90 again starts.

The vent valve 19 consists of a housing 38 secured to the side of the controller housing and provided with an inlet 39 connected to the vent pipe 18 and with an outlet 40 connected to an exhaust drip pipe 105 41.

Between the inlet and the outlet is a vertical passage 42 having a small port 43 at its upper end. This port is controlled 110 by a ball valve 44 which is held up against its seat and normally closing the port 43 by an enclosed compression spring 45.

When the compressor is operating the valve is closed and no air can escape through the vent valve. To open the vent valve when the motor stops, I provide a plunger rod 46 mounted vertically above the valve 44 and guided up and down in the casing 38. This rod has a small diameter stem 47 at its lower end which rests upon the ball 44. For depressing the rod 46 and pushing the valve 44 down from its seat to vent the chamber 13, I provide a rigid projection 48 extending laterally from the end 28 of the lever 25. This projection is arranged to contact with the upper end of the rod 46 when the end 28 of the lever 25 is depressed to stop the motor. The valve having been closed when the compressor 120 was operating the air in the chamber 13 is 125 130

at maximum pressure and when the motor is stopped and the vent valve opened the air escapes from the chamber 13 through the vent valve and reduces the pressure in the chamber 13 to substantially atmospheric pressure.

The air is prevented from escaping from the tank 7 by the check valve 15.

As the vent pipe 18 connects with the chamber 13 at its lowest point 17 the first action of the pressure in the chamber 13 when the vent valve is opened is to force all of the collected or trapped liquid out of the chamber 13 past the valve 44 and then the air escapes from the chamber 13. The opening of valve 44 occurs when the motor stops as previously described, the plunger 46 being actuated by the projection 48 on the motor stopping lever 25 for forcing the ball 44 downwardly against the spring therebeneath.

The arrangement is very simple and effective. The motor can start up freely and easily and the air in the tank 7 is maintained free of all moisture and oil and consequently does not require any attention to prevent water or oil being forced into the tires which are filled with the compressed air.

As many modifications of my invention will readily suggest themselves to one skilled in the art, I do not limit or confine my invention to the specific structures herein shown and described.

I claim:

1. In an air compressing system, a compressor, a receiver for the compressed air, a chamber interposed between the receiver and the compressor, the chamber having an inclined bottom, the connection of the chamber with the compressor being arranged above a high part of the inclined bot-

tom, a transversely extending baffle in the chamber depending from the top wall adjacent to the inlet and ending adjacent to the inclined bottom, the outlet for the receiver arranged on the opposite side of said baffle to cause the air to flow in contact with the inclined bottom and to deposit thereon any carried liquid, and means for discharging collected liquid from said chamber.

2. In an air compressing system, a compressor, a receiver for the compressed air, a chamber interposed between the receiver and the compressor, the chamber having an inclined bottom, the connection of the chamber with the compressor being arranged above a high part of the inclined bottom, a transversely extending baffle in the chamber depending from the top wall adjacent to the inlet and ending adjacent to the inclined bottom, the outlet for the receiver arranged on the opposite side of said baffle to cause the air to flow in contact with the inclined bottom and to deposit thereon any carried liquid.

3. In an air compressing system, a compressor, a receiver for the compressed air, a chamber interposed between the receiver and the compressor, the chamber having an inclined bottom, the connection of the chamber with the compressor being arranged above a high part of the inclined bottom, transversely extending baffles in the chamber, an outlet for the receiver arranged on the opposite side of said baffles to cause air to flow in contact with the inclined bottom and to deposit thereon any carried liquid.

Signed at Chicago, Illinois, this 16th day of May, 1920.

HORACE H. KOUKA.
